UNITED STATES PATENT OFFICE.

JOHN SLATER, OF NEW YORK, N. Y.

DESIGN FOR AN ARCH-SPRING FOR SHOES.

SPECIFICATION forming part of Design No. 33,605, dated November 20, 1900.

Application filed October 24, 1900. Serial No. 34,221. Term of patent 7 years.

To all whom it may concern:

Be it known that I, JOHN SLATER, a subject of the Queen of Great Britain, residing at New York, in the county of New York and State 5 of New York, have invented and produced a new and original Design for an Arch-Spring for Shoes; and I do hereby declare the following to be a full, clear, and exact description of the same, reference being had to the accompanying drawings, forming a part thereof.

My invention relates to a new and original design for arch-springs for use inside of shoes, and its leading and material features will be fully understood from the following description and claim when taken in conjunction with the accompanying drawings, in which—

Figure 1 is a perspective view of an arch-spring, showing my new design. Fig. 2 is a section taken in the plane indicated by the broken line 2 2 of Fig. 1 and illustrating the longitudinal curvature of the spring. Fig. 3 is a section taken in the plane indicated by the broken line 3 3 of Fig. 1 and illustrating the shape of the spring in transverse section at 25 and adjacent to its middle. Fig. 4 is a transverse section taken in the plane indicated by the broken line 4 4 of Fig. 1 and illustrating the transverse curvature of the spring adjacent to the rear end thereof.

In said drawings similar letters of reference 30 designate corresponding parts in all of the views.

As shown in the drawings, the arch-spring is cruciform in outline and comprises a central portion *a*, a rearwardly-extending arm *b*, a forwardly-extending arm *c*, and lateral arms *d* *e*. It is curved in the direction of its length, after the manner best shown in Fig. 2, so that its central portion *a* rests in a plane considerably above that of its arms *b* and *c*, 35 and is also curved slightly in the direction of its width, so that its arms *b* *c* are concavo-convex in cross-section with concave upper sides, while its central portion is concavo-convex with a convex upper side. The lateral arm *e* extends outwardly and thence upwardly with reference to the central portion *a*, while the opposite lateral arm *d*, which is curved to a greater extent than the arm *e*, 40 extends outwardly from the central portion 45 *a* and thence upwardly to a point in a plane considerably above that of the outer end of said arm *e*, as best shown in Fig. 3.

Having described my invention, what I claim as new, and desire to secure by Letters 50 Patent, is—

The design for an arch-spring, as herein shown and described.

In testimony whereof I affix my signature in presence of two witnesses.

JOHN SLATER.
